UNITED STATES PATENT OFFICE.

ELROY A. CHASE, OF NORTHFIELD, VERMONT.

BUFFING WHEEL.

Application filed February 14, 1922. Serial No. 536,532.

To all whom it may concern:

Be it known that I, ELROY A. CHASE, a citizen of the United States, residing at Northfield, in the county of Washington and State of Vermont, have invented a new and useful Buffing Wheel, of which the following is a specification.

This invention relates to a wheel for buffing or polishing blocks of granite or other similar material. In polishing such blocks, the surface to be buffed is commonly not an exact plane surface but contains slightly raised or lowered portions which interfere with the production of a uniform 15 finish.

It is the object of my invention to provide a buffing wheel having a yieldable surface of improved construction, so designed that it will readily yield to pass over a 20 raised portion of the stone and will promptly re-act to engage a depressed portion, thus quickly producing a satisfactory uniform polish.

With this general object in view, my invention further relates to arrangements and combinations of parts which will be hereinafter described and more particularly pointed out in the appended claims.

A preferred form of my improved wheel 30 is shown in the drawings in which

Fig. 1 is a plan view thereof;

Fig. 2 is a sectional elevation, taken along the line 2—2 in Fig. 1;

Fig. 3 is a sectional elevation taken along the line 3—3 in Fig. 1;

Figs. 4 and 5 are perspective views of separate elements of my improved wheel; and

Fig. 6 is a sectional elevation, taken along the line 6—6 in Fig. 1.

Referring to the drawings, I have shown a buffing wheel comprising a rigid frame within which are secured a large number of separately yieldable polishing elements.

The frame 10 comprises an annular flange 11 and a plurality of concentric rings 12, secured to the flange 11 by radial arms 13. A driving attachment 14 is provided at the center of the wheel, the attachment 14 being 45 connected with the flange 11 by arms 15 (Fig. 6) preferably having an inclined or helical under surface.

The arms 15 are separated by openings 16 through which buffing or polishing powder 55 may be fed to the center of the wheel. The propeller-like arms 15 act to carry the pow-

der downward and to deliver the same under the inner edges of the working or polishing face.

The polishing or buffing elements 20 are 60 preferably formed of felt or some other suitable yielding or cushion-like material and are provided with shoulders 21.

Blocks 22 of felt or other material are provided for separating the buffing elements 65 20, these parts 20 and 22 being alternately arranged in the annular openings between the rings 12, as clearly shown in Fig. 3.

The parts 20 and 22 are of such thickness 70 that they may be forced into the openings between the rings, the shoulders 21 engaging the lower faces of the rings and preventing upward displacement of the parts 20 under polishing pressure.

With the polishing elements 20 thus in 75 spaced arrangement each separate element is permitted to yield, as indicated in Fig. 3, whenever a slightly raised portion of the surface to be polished is encountered and similarly the parts will straighten out to 80 reach a depressed surface as they pass over the same.

This construction, while exceedingly simple, is found to result in very great advantage in use, the time of polishing a 85 granite block being very materially reduced by the use of this improved wheel.

Having thus described my invention, it will be evident that changes and modifications can be made therein by those skilled 90 in the art within the spirit and scope of my invention as set forth in the claims, and I do not wish to be otherwise limited to the details herein disclosed but what I claim is:—

1. A buffing wheel comprising a rigid rotatable frame and a plurality of flexible buffing elements mounted therein and spaced apart both circumferentially and radially on the face of said wheel, the circumferentially spacing elements being flexible and all of said elements being relatively small in cross-section and being separately yieldable both radially and circumferentially when engaged by the work.

2. A buffing wheel comprising a frame having a plurality of relatively narrow circumferential openings therein and a plurality of buffing elements secured in each of said openings, the work engaging portions of said elements being spaced apart both radially and circumferentially to permit

separate yielding movement thereof when engaged by the work, the circumferentially spacing elements being flexible.

3. A buffering wheel comprising a frame having a plurality of concentric circular openings therein, a plurality of yieldable buffering elements secured in each separate opening, and flexible spacing elements separating adjacent buffering elements and permitting circumferential yielding movement of the work engaging portions of said buffering elements.

4. A buffering wheel comprising a frame having an annular flange, radial arms projecting therefrom, a plurality of concentric rings mounted underneath said arms and providing continuous circular openings between said rings, and buffering elements and

spacing devices alternately secured in the openings between said rings, each buffering element being of relatively small cross-section and being separately yieldable both radially and circumferentially.

5. A buffering wheel comprising a frame having an annular flange, radial arms projecting therefrom, a plurality of concentric rings mounted underneath said arms and providing continuous circular openings between said rings, and flexible buffering elements and flexible spacing devices alternately secured in the openings between said rings, and being separately yieldable both radially and circumferentially.

In testimony whereof I have hereunto affixed my signature.

ELROY A. CHASE.
